UNITED STATES PATENT OFFICE.

HERMON E. JAMISON, OF WILMORE, KENTUCKY, ASSIGNOR OF ONE-FOURTH TO C. W. MITCHELL, OF WILMORE, KENTUCKY.

TRAIN-CONTROL MECHANISM.

1,416,470.

Specification of Letters Patent. Patented May 16, 1922.

Application filed September 24, 1921. Serial No. 502,901.

To all whom it may concern:

Be it known that I, HERMON E. JAMISON, a citizen of the United States, residing at Wilmore, in the county of Jessamine and State of Kentucky, have invented certain new and useful Improvements in Train-Control Mechanisms, of which the following is a specification, reference being had therein to the accompanying drawings.

10 This invention relates to train control mechanisms and has for an object to provide a device to be attached to a locomotive to shut off the power and apply the brakes when the locomotive runs onto or past an adverse signal.

A further object of the invention is to provide an improved form of mechanism for closing the throttle valve of a locomotive without manual assistance and simultaneously applying the air for stopping or checking a train passing an adverse block.

A further object of the invention is to provide, in combination with a locomotive, an electrically-operated winding drum having a local circuit for actuating the same, with improved means for closing the local circuit when the locomotive passes an adverse block and to translate the motion of such winding drum into means for closing the throttle and applying the air.

With these and other objects in view the invention comprises certain novel parts, units, elements, combinations, functions, mechanical movements and arrangements, as shown in the drawing, together with mechanical equivalents thereof, as will be hereinafter more fully described and claimed.

In the drawings:

Figure 1 is a view in top plan of the improved mechanism associated with such parts of a locomotive as are necessary to show its operation;

Figure 2 is a view of the device in side elevation showing the electrical connections in diagram and conventional parts of a locomotive, the parts being set in running position;

Figure 3 is a view in side elevation of the members shown at Figure 2 but in position acquired by the entering on an adverse block;

Figure 4 is a view of the cam which separates the parts of the structure, shown from the side opposite that seen at Figure 3;

Figure 5 is a perspective view of one of the latch members;

Figure 6 is a perspective view of one of the switches and air valve;

Figure 7 is a top plan view of the throttle and its connection;

Figure 8 is a view in side elevation of the pony wheels of a locomotive entering upon and engaging a ramp for operating the device, and

Figure 9 is a sectional view through a rail and the ramp showing the pony wheel in edge elevation, as indicated by line 9—9 of Figure 8.

Like characters of reference indicate corresponding parts throughout the several views.

The present application is intended as a companion to application Serial No. 493,293, filed August 19, 1921, the structure in that application being shown for energizing the

track circuits, while the present application is for employing an energized ramp connected in such circuit organization. The ramp as shown comprises a bar 20 preferably positioned beside the rail 21 and supported upon any yielding member, as the springs 22. The feature of the ramp rail is shown more particularly at Figures 8 and 9 and is connected by means of a wire 23

with a source of electrical energy 24, as shown more particularly at Figure 2. It

will be obvious that the other side of the source of energy will be grounded through the locomotive in the manner hereinafter explained. The manner of conveying the current from the ramp 20 to the locomotive will

preferably be by means of a disk or ring 25 secured to but insulated from the wheel 26

with a connection 27 to the magnet 28 carried upon the locomotive. It is obvious, therefore, that when the ring 25 strikes the

ramp 20 the circuit from the source of energy 24 to the magnet 28 is closed.

The magnet 28, normally de-energized, is provided with an armature 29, normally held out of engagement with the magnet by a spring 30.

When, however, the magnet 28 is energized, as above noted, the armature 29 is attracted and a latch 31 engages over the extremity of said armature, the movement being from the position shown at Figure 2 to that shown at Figure 3. The latch 31 is actuated by a spring 32 and

manual means indicated as the ring 33 is provided for unlatching the armature 29.

The ramp rail 20 is intended to be but a very short section so that current from the source 24 to the magnet 28 is only momentarily employed to attract the armature 29. When the armature 29 is attracted and locked by the latch 31 the contact 34 carried thereby is in engagement with the 10 spring contact 35, as shown at Figure 3, so that circuit from the local battery 36 to the motor 37 is closed by said contacts, the current passing from the battery 36 through the wire 38 to the contacts and 15 from the contacts through the wire 39 to the switch 40, to be hereinafter more fully described, to the motor 37.

The motor 37 is provided with a drum 41 with a cable 42 wound about said drum 20 and preferably provided with a counter-weight 43.

The cable 42 extends from the drum 41 to an ear 44 rigidly attached to the latch-bar 45 sliding in the keepers 46 and 47. 25 As the cable 42 is wound upon the drum 41 under the action of the motor 37, the latch-bar 45 is moved from full to dotted line position, as shown at Figures 1 and 2. The latch-bar 45 is provided with a pintle 48 which slides in a cam slot 49 formed in the supporting structure. The latch-bar 45 is provided with a finger 50 at its extremity, proportioned to engage in a notch 51 in the bar 52. The bar 52 is connected with the 30 throttle-valve lever 53 through the mechanism to be hereinafter more fully described. The bar 52 slides through a keeper 54 and through the keeper 47, normally in intimate engagement with the under side of the latch 35 bar 45. When the latch-bar 45 is drawn by the winding of the cable 42 upon the drum 41, the latch-bar is drawn longitudinally, as hereinafter described, the pin 48 holding the finger 50 in engagement with the 40 notch 51 and, therefore, drawing therewith the bar 52 to actuate the throttle-valve lever 53. From the formation of the extreme end of the cam slot 49, however, it will be noted that when the bar 52 has been drawn to 45 such a position as to move the throttle-valve to dotted line position, shown at Figure 1, and shut off the steam, the finger 50 will be released from engagement with the bar 52 by lifting the latch-bar 45, as shown at 50 Figure 3. The latch-bar will, however, continue to move farther after such release and the end will engage against the nose 55 of the lever 56. The lever 56 is fulcrumed upon a turning plug 57 of the valve 58 in the 55 air line 59. The kick of the latch-bar 45 against the nose 55 of the lever 56 will, therefore, move such lever from the position shown at Figure 2 with the air line closed, to the open position shown at Figure 3. 60 The lever 56 carries an arcuate contact bar 65

60 engaging between the contacts 61 and 62, which parts constitute the switch, heretofore referred to in its entirety by the numeral 40.

As shown at Figure 3 the parts have been moved to the position to close the throttle 70 and open the air line, but the contact bar 60 is still interposed between the contacts 61 and 62 and a further and additional and final movement to the dotted line position is employed to open such switch. 75

The switch 40 being opened the motor 37 is de-energized and the latch-bar 45 may be returned to normal or running position by stress exerted upon the rod 63. It will be understood, of course, that the manual 80 rods 63 and 33 will extend within the cab and into position for actuation by the engine driver.

The throttle-valve 53 is provided with a detent bar 64 with the usual and ordinary 85 manual hand member 65. The bar 52 is connected by means of a link 66 with a bell crank lever 67, which is pivoted to the throttle-valve lever 53 at 68, and to the detent bar 64 at 69. It will, therefore, be apparent 90 that when the bar 52 is drawn by and in engagement with the latch-bar 45, the first pull will be upon the bell crank lever 67 and by reason of its pivoting will displace the detent from the segment 70 and that the continued pull will move the throttle-valve lever to the dotted line position shown at Figure 1, the movement of the detent and bell crank lever being shown explanatorily at 95 Figure 7.

The movement of the throttle-valve lever to the dotted line position will shut off the steam from the steam chest and, as has been heretofore described, will simultaneously apply the air. 100

The operation of the device is accomplished by the engagement of the parts with the charged ramp rail 20 energizing the magnet 28 to attract the armature 29 and close the local circuit. The passing of the 110 locomotive over the charged rail, however, has no effect upon the operation of the device. The closing of the local circuit will close the throttle-valve and apply the air, as stated, and as a final movement will open 115 the local circuit, so that current of even the local circuit will be only momentarily employed. The parts being moved, as stated, to the position to shut off the steam and apply the air, are returned to normal by the 120 application of stress to the ring 33 to release the armature 29 and the circuit closed thereby, and by the application of stress to the rod 63 to draw the latch-bar 45 to normal or running position. The bar 52 and the latch-bar 45 are actuated with the throttle-valve and manually operated. 125

What I claim is:

1. The combination with a vehicle carrying a source of electrical energy, of a motor, 130

means actuated from contact with an object external of the vehicle for closing a local circuit with the source of energy and the motor, a throttle valve lever, a sliding bar composed of separable parts connected with the throttle valve lever, and means connecting the bar with the motor to move the bar and throttle valve lever to the limit of the lever and means to disconnect the members 10 of the bar upon a further movement.

2. The combination with a locomotive embodying a throttle valve lever and an air-brake system including a valve lever, of a motor carried by the locomotive adapted 15 when energized to move the throttle valve lever and open the air valve by engagement with the lever, a local circuit including the motor a source of energy and two switches, manual means for releasing one of the 20 switches for closing by continuous tension thereon, means actuated from contact with an object external of the locomotive for closing the other of said switches and the circuit to energize the motor, and means operated 25 from the operation of the motor for opening the said first-mentioned switch.

3. The combination with a locomotive embodying a throttle-valve and an air brake system including a valve, of a bar slidable 30 relative to the locomotive and connected

with the throttle valve and positioned to engage and open the air valve when moved to approximately its limit, a motor adapted when energized to move the bar, a circuit for energizing the motor broken by the movement of the bar, and manual means for restoring the condition of the circuit. 35

4. The combination with a locomotive embodying a throttle-valve and an air valve, of a sliding bar composed of separable parts, 40 one of which is connected to the throttle-valve, the other positioned to engage and open the air valve, a motor, means connecting the motor to one of the components of said bar to move the bar to perform said 45 function, means whereby the movement of the bar separates the component elements, a circuit for the motor, a switch interposed in the circuit and opened by the bar at its extreme movement, a second switch in said circuit, electrical means for closing said second switch, and means contiguous to the line of travel of said locomotive for energizing said 50 electrical means.

In testimony whereof I hereunto affix my 55 signature in presence of two witnesses.

HERMON E. JAMISON.
